[57] CLAIM

The ornamental design for a clamp for an article hanger, substantially as shown and described.

DESCRIPTION

FIG. 1 is a front elevational view of a clamp for an article hanger showing my new design, the clamp and hanger being shown in broken lines for illustrative purposes only;

FIG. 2 is a top plan view thereof;

FIG. 3 is a bottom plan view thereof;

FIG. 4 is an enlarged left side elevational view thereof, the side opposite being a mirror image;

FIG. 5 is an enlarged sectional view taken in the direction of the arrows on line V—V of FIG. 4.

The front and rear of the clamp are identical.
